UNITED STATES PATENT OFFICE.

JOHN M. FITZGERALD, OF RIVER FOREST, ILLINOIS.

STORAGE AND DISPENSING TANK FOR LIQUIDS.

Application filed January 31, 1921. Serial No. 441,150.

To all whom it may concern:

Be it known that I, JOHN M. FITZGERALD, a citizen of the United States, and a resident of River Forest, Cook County, Illinois, have 5 invented certain new and useful Improvements in Storage and Dispensing Tanks for Liquids, of which the following is a specification.

My invention relates to tanks or receptacles for the storage and dispensing of liquids and has an important application in connection with volatile and inflammable products such as gasoline and other hydrocarbon oils.

10 The principal objects of the present improvements are the provision of a tank or receptacle having means for easy and rapid filling and discharge which is permanently liquid-tight through the employment of a 15 light-weight inner sheet-metal tank and which may nevertheless be safely embedded in the ground and be thus located in an out-of-the-way position with notable security to the contents and have long life in service; 20 also a device which is strong and well able to withstand the strains and impacts incident to shipment and installation; also a device which is peculiarly free from the danger of explosion or loss through fire due 25 to the ignition of escaping vapors or the presence of heat sufficient to fire the liquid contents of ordinary forms of tanks; also a device in which the filling and dispensing elements or parts are themselves housed 30 safely within the structure and well secured against unauthorized tampering or use; and, withal, a tank device of simple construction and of relatively few parts, and of parts which may readily be assembled 35 40 and taken apart as occasion may suggest. Other objects and advantages will appear hereinafter.

In the accompanying drawings, which form a part of this specification, Figure 1 45 is a perspective view of the device with elements of the tank wall construction, cover, etc., broken away; Fig. 2 is a vertical medial section through the upper portion of the tank and associated parts, the pump being 50 omitted; Fig. 3 is a perspective of a pot-like closure device providing a receptacle and base for holding hand-operable parts of the pump and filling-gate device; Fig. 4 is 55 an enlarged vertical medial section of the filling-gate device; and Fig. 5 is a view of the underside of the outer cover.

The tank or receptacle 10 illustrated has a relatively large cylindrical body portion and a relatively small and diametrically-reduced neck portion connected to each other by a sloping shoulder portion, the general shape of the container 10 being well known. It is formed, in my practice, by making first a liquid-tight inner tank 11 of light-weight galvanized iron, the inner tank having a 60 circular bottom, a vertical cylindrical body, a conically tapering shoulder portion and a vertical cylindrical reduced neck portion, the inner tank having the same general shape as the tank complete and defining the 65 interior shape and surface thereof throughout. This lining 11 may be made according to practices well understood in the sheet metal art.

The inner tank or lining 11 is next surrounded by a reinforcing metal frame having also the same shape as the tank body complete and comprising upright rods 12 and circumferential rods 13. There are also reinforcing cross rods 14 for the bottom, the 70 latter being applied after the iron tank or lining 11 has been inserted in the frame 75 12-13.

The iron tank 11 and its surrounding frame 12-13-14 are then placed with the 80 neck or mouth portion downward in a surrounding sectional mold having the shape and proportions of the outside of the completed tank structure, and thereupon cementitious material (in my practice made 85 of Portland cement and aggregate) is applied within the mold so as to surround the metal tank 11 and embed the frame 12-13. A bottom layer of the plastic material is 90 then added and the cast is allowed to harden. 95

The structure thus formed is exceedingly strong, and, while being liquid-tight in such a highly desirable way as by the provision of a light-weight sheet metal shell, the shell 100 itself is maintained out of contact with destructive salts and acids of the earth and thereby saved from corrosion. Importantly, too, in case of fire or severe blows where the device is used in such places as garages or otherwise above ground the contents of the 105 vessel are well protected by the relatively thick concrete walls.

An important feature of the construction is the provision of filling and dispensing apparatus which is safely and securely 110 housed within the device itself, thus avoiding the presence outside of the tank of pipes,

pumps, valves and other elements subject to being tampered with or to unauthorized use. To this end I provide a cast iron pot-like open-top receptacle having downwardly and inwardly sloping side walls 15, a top flange 16 adapted to overlie the top edge of the neck-wall of the tank, and a bottom wall 17 having a flanged opening 18 for a filling plug and a flanged opening 19 adapted to receive the pump 20. This pot-like device constitutes the closure for the main body portion of the tank. It provides also a base for supporting certain hand-operable parts, and it constitutes also a housing or receptacle for pump elements, etc. An important advantage of its provision is the safety it affords the inflammable contents of the tank in case of fire nearby when only the neck portion of the tank is exposed, as in Fig. 1, a materially large dead-air space being thus interposed between the tank contents and the fire.

In order to hold the pot-like member 15 tightly, securely and readily removably within the neck of the tank I provide four bolts 22 which are embedded in the concrete when cast and which project normally vertically upward. A gasket 23 of soft material such as cork is first placed upon the top surface of the neck wall and the flange 16 of the pot-like member is applied to rest upon the packing 23, the flange 16 having holes 24 for the bolts 22. Thereupon nuts 25 are applied to the bolts and the pot-like member 15 is held in tight and secure relation upon and within the neck portion of the tank.

The device comprises also a flanged overlying cover 26, made in my practice of cast iron. It is held at one place upon the flange 16 of the pot-like member through the provision of an extension of the cover having a recess shown at 27 (Figs. 2 and 5) which engage a rib or projection 28 on a similarly extended part of the flange 16, these two parts interlocking with each other there when in operative position while being readily separable. Diametrically opposite to this interlocking device I secure the cover 26 by means of a padlock 30 the shackle of which passes through a hole in a normally downwardly projecting web 31 integral with the cover. This web 31 interfits with the recess 32 in the flange 16 (Fig. 3) and the extensions 34 of the flange 16 enter the recesses 35 defined by the flange 36 of the cover 26.

It is pointed out that the nuts 25, or the upper ends of the bolts 22, form seats upon which the cover 26 rests, thus spacing the cover from the flange 16 and providing means for the escape of any pressure which may be generated through the volitilization of such liquid contents as naphtha or gasoline.

The filling device shown in Fig. 4 comprises a simple screw plug 34 threaded into the gateway 18. It has a vent opening 35 for the escape of pressure from the main body of the tank. A strainer 36 is also shown.

The piston pump 20, which may be considered as of well-known operative parts, has an operating handle 36 which is available for use only when the overlying cover is removed. A pipe 37 leads from the pump cylinder to the bottom of the tank. A flexible pipe or hose 38 leads from the discharge port of the pump, and is coiled within the receptacle 15 when not in use. This flexible pipe 38 and the can shown by dotted lines in Fig. 1 illustrate how a supply of the liquid may be obtained upon removing the cover 26. The pump is bolted upon the flange around the opening 19 and may readily be removed.

The pot-like receptacle may also be readily removed, for gaining access to the main body interior of the tank, and in such case the pump and filling device come away bodily with it.

An important use for a device of this kind is in railroad practice where supplies of oil, gasoline, etc., must be maintained at intervals along the right of way. The principal desiderata in that service, and which are met by my improved construction, are a relatively large supply, provision against the danger of theft of the product and against the danger of explosions or other conflagrations through fires caused by passing locomotives, provisions for easy filling and discharge, strength, ease of handling, and length of life in service. While I am aware that various details and parts of my improved device are separately well known I have thus provided a structure of unusual advantage in the uses for which it has been designed.

Reference should be had to the appended claims to determine the scope of the improvements herein set forth.

I claim:

1. As a new article of manufacture a storage and dispensing tank having a diaphragm dividing it into an upper chamber and a lower chamber, the upper chamber being open at the top, hand-operable liquid-filling means and hand-operable liquid-dispensing means carried bodily by said diaphragm so as to be removable with the diaphragm from the tank when the diaphragm is removed, said means respectively having all of their hand-operable parts within the upper chamber, a cover overlying the upper chamber whereby access may not be had to said hand-operable parts except upon removal of said cover, and means protected by the cover when the cover is in operative position for holding the dia- 130

phragm readily removably in its operative position.

2. As a new article of manufacture a storage and dispensing tank having a lower 5 relatively large body portion and an upper relatively small neck portion open at the top, a removable cover overlying the neck portion, an open-top pot-like closure-and-receptacle device readily removably held 10 within the neck portion and forming substantially a closure for the body portion, hand-operable filling and dispensing apparatus carried bodily by said pot-like device within the area of said neck portion and 15 removable from the tank when said pot-like device is removed.

3. As a new article of manufacture a storage and dispensing tank comprising a liquid-tight inner tank of sheet metal, there 20 being on said inner tank a substantially heavy reinforced coating of concrete or the like, means in liquid-tight association with the tank walls for dividing the tank into an upper chamber and a lower chamber, the 25 upper chamber being open at the top, an overlying cover for the upper chamber, and filling and dispensing apparatus carried by said tank-dividing means and having hand-operable parts in said upper chamber, said 30 hand-operable parts being entirely within the upper chamber when said overlying cover is in its tank-closing position.

4. As a new article of manufacture a cast monolithic open-top tank having a 35 liquid-tight lining, means forming a dead-air chamber in the normally upper portion thereof, said upper portion being open at the top, said means including a readily removable intermediate diaphragm in liquid-tight relation to the tank walls and an upper 40 cover readily removably mounted for convenient access to said upper chamber, the diaphragm being mounted for removal only upon removal of the upper cover to gain access to the lower chamber of the 45 tank.

5. The combination of walls forming a tank having a relatively large body portion and a relatively small neck portion extending upward and open at the top, an 50 intermediate closure device having a bottom wall and side walls and extending downward into said neck portion, said closure device having an annular flange overlying the top wall of the neck portion and 55 held thereby, and a top cover overlying said annular flange and the top wall of the tank, said top cover having depending flanges overlying the upper sides of said neck portion near the top thereof, and means for 60 holding said top cover removably upon the device.

JOHN M. FITZGERALD.
